US0D1037586S

(12) **United States Design Patent** (10) **Patent No.:** **US D1,037,586 S**
(45) **Date of Patent:** **** Jul. 30, 2024**

(54) **VACUUM CLEANER PART**

(71) Applicant: **Dyson Technology Limited**, Wiltshire (GB)

(72) Inventors: **Davide Leoni**, Bristol (GB); **Stuart Michael John Thompson**, Bath (GB)

(73) Assignee: **Dyson Technology Limited**, Wiltshire (GB)

(**) Term: **15 Years**

(21) Appl. No.: **29/835,444**

(22) Filed: **Apr. 19, 2022**

(30) **Foreign Application Priority Data**

Oct. 26, 2021 (EM) 008736409-0003

(51) **LOC (14) Cl.** **15-05**

(52) **U.S. Cl.**

USPC **D32/33**

(58) **Field of Classification Search**

(57) **CLAIM**

The ornamental design for a vacuum cleaner part, as shown and described.

DESCRIPTION

FIG. 1 is a first side view of a vacuum cleaner part, illustrating our new design;

FIG. 2 is a rear view thereof;

FIG. 3 is a second side view thereof;

FIG. 4 is a third side view thereof;

FIG. 5 is a front view thereof;

FIG. 6 is a perspective view thereof; and,

FIG. 7 is another perspective view thereof.

The broken lines illustrate portions of the vacuum cleaner part that form no part of the claimed design.
